DARWIN'S 4001

UNITED STATES PATENT OFFICE.

OTTO F. FOGELSTRAND, OF KENSINGTON, CONNECTICUT, ASSIGNOR TO
HART MANUFACTURING COMPANY, OF SAME PLACE.

DESIGN FOR SHOVEL-AND-TONGS STAND.

Specification forming part of Design No. 6,193, dated October 8, 1872.

To all whom it may concern:

Be it known that I, OTTO F. FOGELSTRAND, of Kensington, in the county of Hartford and State of Connecticut, have invented a Design for a Shovel-and-Tongs Stand, of which the following is a specification:

The nature of my design is fully represented in the accompanying drawing, to which reference is made.

A represents the base, B the upright, and C C the arms, for supporting the shovel and

tongs. The contour of each part is clearly shown in the drawing, said parts being ornamented with raised work.

I claim as my invention—

The design for a shovel-and-tongs stand, as shown in the drawing.

OTTO F. FOGELSTRAND.
